(57) **CLAIM**

The ornamental design for a cell phone shaped scale, as shown and described.

DESCRIPTION

FIG. 1 is a perspective view of the cell phone shaped scale in a closed position according to the new design.

FIG. 2 is a top view of the cell phone shaped scale in the closed position.

FIG. 3 is a bottom view of the cell phone shaped scale in the closed position.

FIG. 4 is a right side view of the cell phone shaped scale in the closed position.

FIG. 5 is a left side view of the cell phone shaped scale in the closed position.

FIG. 6 is a perspective view of the cell phone shaped scale in an open position.

FIG. 7 is a top view of the cell phone shaped scale in the open position; and,

FIG. 8 is a side view of the cell phone shaped scale in the open position.

The broken line showing of indicia is included for the purpose of illustrating non-claimed subject matter and forms no part of the claimed design.
